J. S. Kenyon,
Sofa Bedstead.

No 56,064.

Patented July 3, 1866.

Inventor;

John S. Kenyon

UNITED STATES PATENT OFFICE.

JOHN S. KENYON, OF WEBSTER CITY, IOWA.

IMPROVEMENT IN SOFA-BEDSTEADS.

Specification forming part of Letters Patent No. **56,064**, dated July 3, 1866.

To all whom it may concern:

Be it known that I, JOHN S. KENYON, of Webster City, in the county of Hamilton and State of Iowa, have invented a new and useful Improvement in Folding-Bedsteads; and I do hereby declare the following to be a full, clear, and exact description of the nature, construction, and operation of the same, reference being had to the accompanying drawings, which are made a part of this specification, and in which—

Figure 1 is a perspective view of my improved folding bedstead in its closed condition. Fig. 2 is a transverse section of the same, the red lines in this figure showing the parts in their open position.

Similar letters of reference indicate corresponding parts in the different figures.

This invention relates to a bedstead which is divided longitudinally in such a way that it may be folded up, and thus converted into a sofa or be laid aside in some convenient spot, so as to occupy but little room.

In order that others skilled in the art to which my invention appertains may be enabled to fully understand and use the same, I will proceed to describe its construction and operation.

In the accompanying drawings, A A' may represent the bed-bottom, which term includes the side and end rails, as well as the slats or other central supporting portion of the bedstead.

B B' represent the head-board, and C C' the foot-board. The bottom A A' is divided longitudinally and hinged at *a a'*, so that the section A' may be turned up into the position shown in Fig. 1. The head and foot boards are hinged at *b* and *c*, respectively, so that when the section A' of the bottom is turned up the sections B' C' of the head and foot boards may be folded in, so as not only to assume a compact form, but sustain the section A' in its upright position.

In turning up the section A' it is detained when upright by a suitable stop or shoulder, *a'*.

Simple cleats on the posts D D may be employed to sustain the outer side of the section A' when the latter is turned down to form the bed-bottom; but instead of such cleats the catches E E may be fixed to the posts D D and made to enter recesses F F in the section A' when the same is turned down.

The recesses F F may be metal-bound on the outer edge.

It is believed that the catches E and recesses F constitute the best fastening, for they not only serve to support the section A', but hold the parts A' B' C' firmly together.

The catches E E need no other description than to say they are strips of metal bent as shown, and secured to the parts by rivets or otherwise.

Any other fastening or supporting device may be used instead of the above.

A metallic spring-catch may be made to hold the sections B' C' together when the bedstead is folded.

The under side of the hinged section A' may be made to imitate panel-work, or otherwise ornamented so as to present a neat appearance when the bedstead is folded up.

In stating the manipulation of this bedstead it is only necessary to say that to convert it into a compact article of neat and ornamental furniture the bottom section A' is first turned into an upright position, and the head and foot board sections B' C' turned at a right angle with the stationary sections B C.

The bedstead thus folded up, with the sections B C presented outward, will constitute a neat and desirable article of furniture.

By turning the bedstead around it may be used as a sofa, in which case the stationary portion A of the bottom will form the seat of the sofa, and the upright section A' the back thereof.

When it is designed to use the bedstead as a sofa special proportions of the several parts should be observed in the construction.

Having thus described my invention, the following is what I claim as new herein and desire to secure by Letters Patent:

1. The hinged bottom A A', in combination with the hinged head and foot boards B B' C C', all arranged to operate substantially as herein specified.

2. In combination with the above, the catches E E and recesses F F, substantially as described.

JOHN S. KENYON.
